UNITED STATES PATENT OFFICE.

LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,220,148.

Specification of Letters Patent. Patented Mar. 20, 1917.

Application filed March 27, 1914. Serial No. 827,539.

To all whom it may concern:

Be it known that I, LESTER A. WERNERY, a citizen of the United States, residing in Brooklyn borough, in the county of Kings, 5 city and State of New York, have invented certain new and useful Improvements in Type-Writing Machines, of which the following is a specification.

This invention relates to appliances for 10 typewriting machines, and, in the form herein specifically disclosed, is particularly adapted for advancing over the platen a work sheet or web, consisting of a series of work-forms adapted to be written upon *seriatim*. 15 The work sheet or device may consist of a number of blank forms connected in a continuous web or long sheet to be advanced over the platen to bring the blank forms *seriatim* into position to be written upon. 20 A feature of the invention is the provision of improved means for quickly and accurately advancing each form into position to be written upon, when the entries on the preceding form have been completed. In 25 the preferred embodiment of the invention, a handle or driver is provided having a limited throw and means coöperating therewith, for advancing the work member to bring a new form into position to receive the first 30 line of writing whenever the driver is actuated to the limit of its forward movement, regardless of the extent the platen has been rotated while entries were being made upon the preceding work-form. 35 The driver may be a crank loosely mounted on the platen axle and its movement in both directions limited by stops, one or both of which may be adjustable to limit the throw of the driver. The driving connection between the driver and the platen may 40 be effected by means of a coupling device, which, in the form disclosed, comprises a dog on the driver adapted to engage the teeth of a ratchet wheel which rotates with the platen. A coupling controller or gage 45 which may be in the form of a disk loose on the platen axle but which may be caused to rotate therewith by frictional engagement, or other appropriate means, lies in the path 50 of the dog and thereby holds the latter out of engagement with the ratchet wheel during the rotation of the platen independently of the operation of the driver, said disk

turning with the platen during such rotation. To advance the completed work-form 55 into position to be removed and to bring a succeeding work-form into position to be printed upon, the driver is swung forward, and during its initial movement, the dog thereon rides idly on said disk, until a notch 60 in the disk permits the dog to spring into engagement with the ratchet wheel so that during the final movement of the driver the platen is rotated therewith. The position of the notch at the time the driver is swung 65 forward to engage the ratchet wheel depends on the distance the platen has been rotated during the writing upon the work-form. The extent the platen is rotated by the driver will therefore be complementary to the 70 angle through which the platen has been rotated prior to the operation of the driver, the total movement of the platen being determined by the total throw of the driver, which is adjusted to the length of the individual work-form. The driver may be returned to initial position by a spring, and a lug on said disk, in front of which the dog drops as it enters into said notch, forms a 75 driving connection between the driver and the disk for returning the latter with the driver. As the driver completes its return movement, the dog may be lifted by a cam to disengage said lug, thereby releasing the disk ready for a subsequent operation. 80 85

Other features and advantages will hereinafter appear; and the invention may be used for other purposes.

In the accompanying drawings,

Figure 1 is a front perspective view showing the platen frame and platen of an Underwood typewriting machine with the present invention attached thereto.

Fig. 2 is a sectional end elevation showing the parts in the position assumed when 95 the driver has completed its return throw.

Fig. 3 is a similar view showing in full lines the driver at the end of its forward throw, and in dotted lines showing the driver just before it has completed its return movement.

Fig. 4 is a disassembled view of the driver and adjoining parts.

Fig. 5 is a sectional elevation of the invention.

Fig. 6 is a detail view of the driving dog.

105

Fig. 7 is a disassembled view showing successively the ratchet wheel, the friction member, the interponent disk between which and the ratchet wheel said friction member 5 is arranged, and a hand wheel.

A rotary platen 1 is fixed to an axle 2 journaled in the ends 3, 4 of the platen frame, said ends connected by an inclined paper shelf 5 at the rear of the platen. The platen may be rotated either by hand wheels 6 on the ends of the platen axle, or by the usual line-space mechanism, comprising a line-space wheel 7 fixed to the platen axle and adapted to be rotated by a pawl 8 pivoted on a slide 9 driven by a line-space lever 10, and returned by a spring 11. A web or other work piece 12 which usually consists of a series of printed work-forms of equal length, is fed over the table 5 and forward 15 between the platen and the usual feed rolls 20 (not shown) into position to receive impressions from the type-bars 46.

After a work-form has been typewritten upon, the platen may be further rotated to bring the next form into position by means 25 of a driver 13 which as herein shown, comprises an arm extending radially from a disk 14 loosely mounted on the platen axle 2, said arm provided at its outer end with 30 a handle 15. A coupling device to establish a driving connection between the driver and the platen is provided, and comprises, in the form disclosed, a ratchet wheel 16 and a dog 18. The ratchet wheel 16 is fixed to 35 the platen axle as by means of a pin extended through the hub 17 of said wheel and through the said axle. A dog 18 slidably mounted on the driver 13 is formed with a beveled tooth 19 to engage the ratchet 40 wheel 16 to drive it in a forward direction, but permits forward rotation of the platen independently of the driver. The dog 18 comprises a neck 20, extending through an elongated slot 21 in the driver, and a plate 45 22 having a slot-and-pin connection 23, 24, with the driver. A stem 25 on the plate 22 is guided in a lug 26 on the driver 13, and a spring 27 surrounding said stem between the lug 26 and the plate 22 moves the dog 50 18 radially inward to engage the ratchet wheel 16.

An interponent between the dog and ratchet wheel 16 for holding the dog off the ratchet wheel is shown in the form of a disk 28 having a hub 29 loosely mounted on the hub 17 of the ratchet wheel, and said disk is substantially of the same diameter as that of the ratchet wheel, so that the periphery of the disk engages the tooth 19 of 55 the dog 18 and holds the latter out of driving engagement with the ratchet wheel, except when said tooth is brought into position to enter a notch 30 in the disk and thus connect the driver with the ratchet wheel. 60 The disk 28 thus constitutes a gage or cou-

pling controlling device for determining the point at which the coupling device shall become effective during the advance movement of the driver. The hub 29 on said disk is frictionally held against the hub of 70 the adjacent hand wheel 6 by means of a spring, shown as a convexed sheet metal ring or disk 31 of resilient material, interposed between the disk 28 and the ratchet wheel 16.

The driver 13 is adapted to oscillate between a rearward stop 32 and a forward stop 33. The stop 32 is shown as a pin secured to a stationary disk 34 loosely mounted on the platen axle. said disk adjustably connected to the platen frame by a turn-buckle connection 35. The forward stop 33 is in the form of a tube secured to, and extending outwardly from a disk 36 loosely mounted on the platen axle between the driver disk 14 and the ratchet wheel 16. Within the tube 33 is a holding pin or bolt 37 adapted to enter any one of an annular series of openings 38, in the disk 34, thereby holding the stop 33 in any desired position relative to the stop 32. The openings 38 may be spaced at line-space intervals. The bolt 37 may be withdrawn by a knob 39 against the tension of a spring 40, housed in the tube 33 and bearing against a 95 collar on the bolt 37.

The driver 13 is normally held against the stop 32 by means of a returning spring 41 shown as a coil spring, housed within the space provided by recessing the opposing faces of the disks 34, 14, one end of said spring secured to the disk 34 and the other end secured to the disk 14. Whenever the driver 13 is returned to starting position (Fig. 2) the disk 28 is carried with it, being connected to the driver by a lug or detent 42 on the outer face of the disk in the path of an overhanging lip 43 projecting beyond the tooth 19.

The operation may be summarized as follows:

The work sheet or web comprising, for example, a series of printed forms or blanks is placed on the machine and the first form positioned to receive the first typewritten entry. The driver 13 and interponent disk 28 being at the starting position shown in Fig. 2, the desired entries are now typewritten upon the work-form, during which operation the platen is rotated by the line-space lever or the hand wheels 6, a greater or less extent depending upon the required entries on the work-form. During such rotation of the platen, the driver 13 remains at rest, the tooth 19 being held free from the ratchet wheel 16 by a cam surface 44 on the disk 34, which surface, as the driver was returned to starting position (Fig. 2) engaged a shoulder 45 on the locking dog and lifted the latter free from the ratchet wheel 130

16. After the entries on the work-form have been completed, the driver is thrown forward until it engages the forward stop 33. During the initial portion of this movement, the tooth 19 rides on the periphery of the disk 28 and is thus held off the ratchet wheel 16 until the tooth 19 reaches the notch 30 and permits the dog to engage said wheel. The continued movement 5 of the driver rotates the platen and brings the next work-form into position to receive the first line of writing. The form that has just been completed may now be removed, if desired.

10 It will be noted that as the platen is rotated prior to the operation of the driver the disk 28 is carried with it and rotated a variable distance determined by the position to which the work-form has been brought by the time the typewritten entries thereon have been completed. The entire distance, however, through which the platen is rotated, determined by the throw of the driver, 13, is constant. In other 15 words, the distance the platen is rotated by the driver is complementary to the distance it is rotated prior to the operation of the driver and the sum of these distances is measured by the distance between the stops 20 32 and 33. These stops may therefore be set for work-forms of any length within the range of the mechanism, so that each time the driver is actuated, a new form is fed into position for receiving the first line of writing. When the tooth 19 enters the notch 30 25 during the forward movement of the driver, the lip 43 moves inward in front of the lug 42, so that when the handle 15 is released and the driver returned by the spring 41, the disk 28 is carried with it until the shoulder 40 45 rides on to the cam face 44 as the driver completes its return movement. Thus the disk 28 is always returned to the same starting position. During the return of the driver, the tooth 19 rides idly over the 45 50 ratchet wheel, so that the platen remains at rest. The teeth on the ratchet wheel do not throw the dog out a sufficient distance during such return movement to free it from the lug 42.

Variations may be resorted to within the scope of the invention, and portions of the improvements may be used without others.

Having thus described my invention, I 55 claim:

1. The combination with a rotatably-mounted platen and a normally uncoupled driver, the platen being rotatable by, and also independently of, the driver, of a normally ineffective coupling device for effecting a driving connection between the driver and the platen, said coupling device being capable of coming into operation at various points in the driving movement of the 60 65 driver, and a coupler controller movable

with the platen independently of the driver for predetermining the point at which the coupling device shall become effective.

2. The combination with a rotary platen, a driver loose on the platen axle, and means to limit the throw of the driver, of a ratchet wheel connected to rotate with the platen, a dog on said driver, to engage said ratchet wheel, and a gage frictionally driven by the platen and holding said dog out of engagement with the ratchet wheel during a portion of the movement of the driver. 70

3. The combination with a rotary platen, a driver loose on the platen axle, and means to limit the throw of the driver, of a ratchet wheel connected to rotate with the platen, a dog on said driver, to engage said ratchet wheel, a gage frictionally driven by the platen and holding said dog out of engagement with the ratchet wheel during a portion of the movement of the driver, and means for causing said gage to be returned 80 85 with the driver to starting position.

4. The combination with a rotary platen, of a driver mounted for rotation independently of the platen, a ratchet wheel connected to rotate with the platen, a dog on the driver to engage said ratchet wheel, and an interponent between the dog and ratchet wheel frictionally held for rotation with 90 95 said ratchet wheel and holding the dog away from the ratchet wheel, said interponent formed to permit the dog to engage the ratchet wheel when the driver has been moved to a predetermined position relative 100 to said interponent.

5. The combination with a rotary platen, of a driver mounted for rotation independently of the platen, a ratchet wheel connected to rotate with the platen, a dog on the driver to engage said ratchet wheel, and a disk frictionally held for rotation with 105 110 said ratchet wheel and holding the dog away from the ratchet wheel, said disk provided with a notch or depression to permit the dog to engage the ratchet wheel when the driver has been moved to a predetermined position relative to said disk.

6. The combination with a platen axle and a platen secured thereto, of a driver 115 loosely mounted for rotation on the platen axle, a ratchet wheel fixed to the platen axle, a dog on said driver having a tooth to engage the ratchet wheel, and a disk frictionally held for rotation with said ratchet wheel and having its periphery in position to engage said tooth and hold the latter off the ratchet wheel, said disk provided with a notch to permit said tooth to engage the ratchet wheel when the driver has been 120 125 moved forward to a position determined by the distance said disk has been rotated relative to the driver.

7. The combination with a platen axle and a platen secured thereto, of a driver 130

loosely mounted for rotation on the platen axle, a ratchet wheel fixed to the platen axle, a dog on said driver having a tooth to engage the ratchet wheel, a disk frictionally held for rotation with said ratchet wheel and having its periphery in position to engage said tooth and hold the latter off the ratchet wheel, said disk provided with a notch to permit said tooth to engage the ratchet wheel when the driver has been moved forward to a position determined by the distance said disk has been rotated relative to the driver, stops to limit the forward and rearward movement of the driver, and means coöperating with the driver to positively return said friction disk when the driver is returned to starting position.

8. The combination with a platen axle and a platen secured thereto, of a driver loosely mounted for rotation on the platen axle, a ratchet wheel fixed to the platen axle, a dog on said driver having a tooth to engage the ratchet wheel, a disk frictionally held for rotation with said ratchet wheel and having its periphery in position to engage said tooth and hold the latter off the ratchet wheel, said disk provided with a notch to receive said tooth and permit the same to engage the ratchet wheel when the driver has been moved forward to a position determined by the distance said disk has been rotated relative to the driver, a lug on said disk in position to engage behind said dog when said tooth is in said notch whereby the disk is returned with the driver, and a cam in position to lift the dog at the completion of the return movement of the driver and thus release the dog from said lug preparatory to a subsequent forward rotation of the disk.

9. The combination with a rotatably-mounted platen and a normally uncoupled driver, the platen being rotatable by, and also independently of, the driver, of a normally ineffective coupling device for effecting a driving connection between the driver and the platen, said coupling device being capable of coming into operation at various points in the driving movement of the driver, a coupler controller movable with the platen independently of the driver for predetermining the point at which the coupling device shall become effective, and means for variably limiting the throw of the driver.

10. The combination with a rotatably-mounted platen, a normally uncoupled driver, and line-spacing mechanism for imparting to the platen initial instalments of rotation independently of the driver, of a stop against which the driver rests during said initial rotation of the platen, a normally ineffective coupling device for effecting a driving connection between the driver and the platen, said coupling device being

capable of coming into operation after, and at a point dependent upon the extent of, said initial rotation by the line-spacing mechanism, to complete a predetermined extent of rotation, and a coupling controller movable with the platen independently of the driver for predetermining the point at which the coupling device shall become effective.

11. The combination with a revoluble platen and a driver normally disconnected from the platen, of a stop against which the driver normally rests during the advance rotation of the platen, a ratchet rotatable with the platen, a pawl carried by said driver, a gage to hold said pawl off the ratchet as the platen is advanced, means to cause said gage to rotate with the ratchet, said gage formed to permit the pawl to engage the ratchet when the driver is advanced, after such advance rotation of the platen, to a position determined by the distance through which the platen has been rotated, and thereby enable the driver to rotate the platen during the remainder of the advance movement of the driver, and a stop to limit the throw of the driver, the distance through which the platen is rotated by the driver being complementary to the distance through which the platen is rotated before the operation of the driver, whereby the total rotation of the platen is through a predetermined fixed distance.

12. The combination with a rotatably-mounted platen, of means to rotate the platen by a cycle of operations through the same predetermined fixed angular distance at each cycle, said rotating means comprising a normally uncoupled driver and line-spacing mechanism to advance the platen independently of the driver, a stop to limit the return movement of the driver and against which it rests during initial rotation of the platen by the line-spacing mechanism, a stop to limit the advance movement of the platen, a normally ineffective coupling device for effecting a driving connection between the driver and the platen, said coupling device being capable of coming into operation after, and at a point dependent upon the extent of, said initial rotation by the line-spacing mechanism, to rotate the platen through a distance complementary to its initial rotation by the line-spacing mechanism, and a coupling controller movable with the platen independently of the driver for predetermining the point at which the coupling device shall become effective, and movable with the driver independently of the platen on return movement of the driver.

13. The combination with a rotatably-mounted platen, of means to rotate the platen by a cycle of operations through the same predetermined fixed angular distance at each cycle, said rotating means comprising a normally uncoupled driver and line-

- spacing mechanism to advance the platen independently of the driver, a stop to limit the return movement of the driver and against which it rests during initial rotation of the platen by the line-spacing mechanism, a stop to limit the advance movement of the platen, a normally ineffective coupling device for effecting a driving connection between the driver and the platen, said coupling device being capable of coming into operation after, and at a point dependent upon the extent of, said initial rotation by the line-spacing mechanism, and a coupling controller movable with the platen independently of the driver for predetermining the point at which the coupling device shall become effective, the point of coupling being advanced on the initial rotation of the platen to an extent corresponding with said initial rotation, whereby the platen is rotated by the driver through an angular distance complementary to the angular distance through which the platen is rotated by the line-spacing mechanism.
14. The combination with a rotatably-mounted platen, of means to rotate the platen by a cycle of operations, the platen being advanced through an angular distance which may be predetermined and set for a succession of cycles of operation, said rotating means comprising a normally uncoupled driver and line-spacing mechanism to advance the platen independently of the driver, a stop to limit the return movement of the driver and against which it rests during initial rotation of the platen by the line-spacing mechanism, an adjustable stop for setting the limit of advance movement of the driver, a normally ineffective coupling device for effecting a driving connection between the driver and the platen, said coupling device being capable of coming into operation after, and at a point dependent upon the extent of, said initial rotation by the line-spacing mechanism, to rotate the platen through a distance complementary to its initial rotation by the line-spacing mechanism, to complete the angular rotation of the cycle as predetermined and set, and a coupling controller movable with the platen independently of the driver for predetermining the point at which the coupling device shall become effective.
15. The combination with a rotatably-mounted platen and a normally uncoupled driver, the platen being rotatable by, and also independently of, the driver, of a normally ineffective coupling device for effecting a driving connection between the driver and the platen, said coupling device being capable of coming into operation at various points in the driving movement of the driver, and a coupler controller movable with the platen independently of the driver for predetermining the point at which the coupling device shall become effective, and movable with the driver independently of the platen on return movement of the driver.
16. The combination, with a platen, and a driver for rotating the same forwardly, said platen being rotatable independently of said driver while the latter is at rest; of a pair of cooperating devices, one connected with the driver, and the other with the platen, for automatically coupling said driver and said platen together for rotation in unison; and a gage rotatable with said platen and directly co-acting with the first-named device for holding the same in ineffective position with relation to the other device during a portion of the movement of the driver.
17. The combination with a rotatably-mounted platen and a normally uncoupled driver, the platen being rotatable by, and also independently of, the driver, of a normally ineffective coupling device for effecting a driving connection between the driver and the platen, said coupling device comprising a dog carried by the driver and a ratchet wheel connected to rotate with the platen, means normally tending to move the dog into engagement with the ratchet wheel at any point in the movement of the driver, and a coupling controller rotatable with said platen and capable of holding said dog out of engagement with the ratchet wheel during a portion of the movement of the driver.
18. The combination with a rotatably-mounted platen and a normally uncoupled driver, the platen being rotatable by, and also independently of, the driver, of a normally ineffective coupling device for effecting a driving connection between the driver and the platen, said coupling device comprising a dog on the driver and a ratchet wheel connected to rotate with the platen, means normally tending to move the dog into engagement with the ratchet wheel at any point in the movement of the driver, and a coupling controller rotatable with the platen and capable of holding said dog out of such engagement with the ratchet wheel, said coupling controller having a depression therein to permit the dog to move into engagement with the ratchet wheel when the driver has traveled through a portion of its active stroke.
19. The combination with a rotatably-mounted platen and a normally uncoupled driver, the platen being rotatable by, and also independently of, the driver, of a normally ineffective coupling device for effecting a driving connection between the driver and the platen, said coupling device comprising a dog carried by the driver and a ratchet wheel connected to rotate with the platen, means normally tending to move the

dog into engagement with the ratchet wheel at any point in the movement of the driver, a coupling controller rotatable with said platen and capable of holding said dog out of engagement with the ratchet wheel during a portion of the movement of the driver, and means for causing said coupling controller to be returned with the driver to starting position.

20. The combination with a rotatably-mounted platen and a normally uncoupled driver, the platen being rotatable by, and also independently of, the driver, of a normally ineffective coupling device for effecting a driving connection between the driver and the platen, said coupling device comprising a dog on the driver and a ratchet wheel connected to rotate with the platen, means normally tending to move the dog into engagement with the ratchet wheel at any point in the movement of the driver, and a coupling controller rotatable with the platen and capable of holding the dog out of engagement with the ratchet wheel, said coupling controller having a depression to permit the dog to move into engagement with the ratchet wheel when the driver has traveled through a portion of its active stroke, and a projection adjacent to said depression to be engaged by the dog to form a driving connection for returning said coupling controller by said driver.

21. The combination with a rotatably-mounted platen and a normally uncoupled driver, the platen being rotatable by, and also independently of, the driver, of a normally ineffective coupling device for effecting a driving connection between the driver and the platen, said coupling device comprising a dog on the driver and a ratchet wheel connected to rotate with the platen, means normally tending to move the dog into engagement with the ratchet wheel at any point in the movement of the driver, means to hold the dog out of engagement with said ratchet wheel when the platen is rotated independently of the driver, and a coupling controller movable with the platen and capable of holding said dog out of engagement with said ratchet wheel during a portion of the movement of the driver, and also capable of permitting said dog to engage said ratchet wheel after said driver has been moved forward a distance corresponding to the aforesaid independent rotary movement of said platen.

22. The combination, with a rotary platen; of a driver therefor, said driver and platen rotatable independently of each other; a ratchet wheel connected to rotate with said platen; a dog on said driver arranged to engage said ratchet wheel, to couple the driver and platen together for rotation in unison; a disk connected to rotate with said platen and normally acting

to hold said dog out of engagement with said ratchet wheel, said disk having a depression to permit said dog to move into engagement with said ratchet wheel when the driver has traveled through a given portion of its active stroke; and a lug on said disk arranged to engage behind said dog when the latter is so engaged with said ratchet wheel, whereby said disk will be returned with said driver.

23. The combination with a rotatably-mounted platen, a normally uncoupled driver, and line-spacing mechanism for imparting to the platen initial instalments of rotation independently of the driver, of a stop against which the driver rests during said initial rotation of the platen, a normally ineffective coupling device for effecting a driving connection between the driver and the platen, said coupling device being capable of coming into operation after, and at a point dependent upon the extent of, said initial rotation by the line-spacing mechanism to complete a predetermined extent of rotation, a coupling controller movable with the platen independently of the driver for predetermining the point at which the coupling device shall become effective, and means for returning the driver and coupling controller to normal position.

24. In combination, a writing mechanism, a platen, a normally uncoupled driver to cause relative movement in line-spacing direction between the writing mechanism and the platen, the writing mechanism and the platen being also relatively movable in line-space direction independently of said driver, a normally ineffective coupling device whereby said driver may effect such independent relative movement between the writing mechanism and the platen; said coupling device being capable of coming into operation at various points in the driving movement of said driver; and means dependent upon the relative movement between the writing mechanism and the platen, independently of said driver, for predetermining the point at which said coupling device shall become effective.

25. In combination, a writing mechanism, a platen, a normally uncoupled driver to cause relative movement in line-spacing direction between the writing mechanism and the platen, the writing mechanism and the platen being also relatively movable in line-space direction independently of said driver, a normally ineffective coupling device whereby said driver may effect such independent relative movement between the writing mechanism and the platen; said coupling device being capable of coming into operation at various points in the driving movement of said driver; means dependent upon the relative movement between the writing mechanism and the platen

platen, independently of said driver, for predetermining the point at which said coupling device shall become effective, and means for variably limiting the stroke of said driver, whereby the relative movement between the platen and writing mechanism may be made in instalments through a predetermined cycle of regulatable extent, the final variable instalment being made by

10 said driver.

26. In combination, a writing mechanism, a platen, a normally uncoupled driver to cause relative movement in line-spacing direction between the writing mechanism and the platen, the writing mechanism and the platen being also relatively movable in line-space direction independently of said driver, a normally ineffective coupling device where-

by said driver may effect such independent relative movement between the writing mechanism and the platen; said coupling device being capable of coming into operation at various points in the driving movement of said driver; and means dependent upon the relative movement between the writing mechanism and the platen, independently of said driver, for predetermining the point at which said coupling device shall become effective, said predetermining means being connected to return with the driver.
